UNITED STATES PATENT OFFICE

FREDERICK A. HART, OF NEW BRITAIN, CONNECTICUT, ASSIGNOR TO REMINGTON TYPE-WRITER COMPANY, OF ILION, NEW YORK, A CORPORATION OF NEW YORK

TYPEWRITING MACHINE

Application filed October 22, 1926. Serial No. 143,382.

My invention relates to typewriting or like machines, and more particularly to so-called billing mechanism therefor.

The machine in which the features of the present invention are embodied has some of the same general objects in view as the constructions disclosed in each of the following applications and patents: Frederick A. Hart, filed July 3, 1926, Ser. No. 120,403 (now Patent 1,650,351); S. L. Walsoe & J. P. Hill, filed July 8, 1926, Ser. No. 121,134 (now Patent 1,650,673); S. L. Walsoe, filed Sept. 2, 1926, Ser. No. 133,228 (now Patent 1,663,362); C. E. Burns, filed July 13, 1926, Ser. No. 122,239 (now Patent 1,647,854).

The present invention is intended primarily to improve the construction disclosed in the said patent of Walsoe, 1,663,362, and includes various features which are combined with those disclosed in said patent. The present invention also includes features that are equally applicable to the construction disclosed in the patents mentioned above, with a view to improving them.

More specifically stated, the objects of the present invention are as follows:

(1st) To convert the so-called two-sheet biller of the Walsoe patent 1,663,362 into a so-called three-sheet biller, by providing a third set of paper feed rollers and means for effectively controlling them for the purposes for which they are employed.

(2nd) By providing simple and effective adjusting means by which the positively applied paper feed rollers may exert more or less force at each application thereof.

(3rd) To provide means for automatically locking the paper feed rollers which coat with the register sheet in ineffective position.

(4th) To provide means for temporarily limiting the movement of the positively applied paper feed rollers away from the platen in a position intermediate the full extent of releasing movement thereof.

(5th) To provide means whereby the movement of a finger piece in one direction is effective to move two sets of feed rollers away from the platen and a movement of the finger piece in the opposite direction is effec-

tive to apply one set only of said feed rollers to the platen.

(6th) To provide means for supporting the ledger sheet in a manner which will more readily facilitate the introduction of a comparatively thin bill or statement sheet. 55

(7th) To provide detenting means for preventing an accidental displacement from the extreme releasing position of the paper feed rollers which automatically control the 60 line indicator, etc.

To the above and other ends which will hereinafter appear, my invention consists in the features of construction, arrangements of parts, and combinations of devices set 65 forth in the following description and particularly pointed out in the appended claims.

In the accompanying drawings wherein like reference characters indicate corresponding parts in the different views: 70

Figure 1 is an enlarged, detail, fragmentary, side elevation of a portion of the machine with parts broken away, the view showing the parts in full lines as they are normally disposed when the machine is in 75 condition for writing.

Figure 2 is a like view of some of the parts disclosed in Fig. 1, but showing such parts as they appear when the machine is conditioned to receive rearwardly introduced work sheets inserted from in front of the platen. 80

Figure 2^a is a detail, fragmentary, side elevation showing a part of the ribbon vibrator supporting and actuating mechanism. 85

Figure 3 corresponds in part to the showing in Fig. 2 except that the forward feed rollers are shown released from the platen while the automatically controlled deflector, line indicator and ribbon vibrator have not been disturbed from the position they normally occupy. 90

Figure 4 is a full size, fragmentary, top plan view of a portion of the machine with the parts shown in normal position. 95

Figure 5 is an enlarged, detail, fragmentary, top plan view showing the left-hand end of the front feed-roller spindle, the as- 100

sociated guide therefor and the spring detent which coacts therewith.

Figure 6 is a fragmentary, vertical, transverse sectional view of the carriage, taken on the line 6—6 of Fig. 1 and looking in the direction of the arrows at said line.

Figure 7 is an enlarged, detail, fragmentary, perspective view of the improved means for adjustably connecting one end of the wire line-indicator to its supporting arm.

Figure 8 is a fragmentary, detail, perspective view of the center of secondary feed rollers and the associated means for mounting and controlling said rollers.

Figure 9 is a detail, perspective view of the double deflector together with the parts carried thereby and some of the parts associated therewith.

Figure 10 is an enlarged, detail, transverse sectional view showing a portion of the double deflector and manner in which it coacts with various work sheets.

Figure 11 is a detail, fragmentary, perspective view, showing the parts by which one of the guides for the forward feed rollers is adjustably supported.

Figure 12 is an enlarged, detail transverse sectional view showing the means for adjustably supporting the double deflector in normal position; the section being taken on the line 12—12 of Fig. 4 and looking in the direction of the arrows at said line.

Figure 13 is an enlarged, detail, fragmentary sectional view of the left-hand end of the spindle for supporting the top feed rollers, together with the associated bearing for this end of said spindle; the section being taken on the line 13—13 of Fig. 1 and looking in the direction of the arrows at said line.

Figure 14 is an enlarged, detail, transverse sectional view of the same, taken on the line 14—14 of Fig. 13 and looking in the direction of the arrows at said line.

The machine in which the features of the present invention are shown embodied is a Remington bookkeeping machine, model No. 23, equipped with automatic carriage return mechanism such as disclosed in my Patent No. 1,567,590, dated Dec. 29, 1925. However, I have shown only so much of said machine, modified to include the toggle controlled paper feed mechanism, etc., of the Walsoe patent hereinbefore referred to, as is necessary to illustrate my invention in its inclusion therein. It should be understood, however, that the invention is not restricted to embodiment in said machine but is of general application wherever found available.

As in the machines of the said patents and applications hereinbefore referred to the present machine is capable of a wide range of uses in connection with various

so-called billing operations and the like, where two or more work sheets are to be correlated in the machine and printed at a single operation. However, I do not deem it necessary to describe specifically the many different forms of billing operations in which the machine may be used. It is sufficient for an understanding of the present invention to specifically describe one mode of billing that may be successfully carried out with the aid of the present machine, and perhaps briefly refer to some of the various other methods in connection with which the machine may be employed.

One method of using the machine, which will be specifically referred to, is its employment for simultaneously, or at one writing, making out a "statement", making corresponding entries on the ledger sheet carrying the account, and on a record or register sheet which receives the various entries written on all of the individual statement and ledger sheets. In the example referred to the register sheet and its accompanying carbon sheet remain in the machine. Means are provided to enable the ledger sheet and its accompanying carbon sheet to be quickly introduced and properly positioned to receive the requisite entries without disturbing the previously introduced register sheet and companion carbon sheet. Means also are provided for then quickly entering a statement sheet into the machine in front of the platen and accurately positioning it in proper correlation with the previously introduced ledger sheet and the printing line. The entries may then be made on the statement sheet and these will be transferred through the interposed carbon sheets to the ledger and register sheets. If desired, additional entries may be made on the ledger sheet which are not to appear on the statement or register sheet. The statement and ledger sheets are then rapidly withdrawn from the machine without disturbing the register sheet and its companion carbon sheet and another ledger sheet and statement sheet may then be quickly introduced, as before, and so on.

A line spacing operation effected by the return of the carriage after writing a statement and making the corresponding entry on the ledger and register sheets, advances the register sheet in position to receive a manifold copy of the next entry on the register sheet.

With the foregoing general explanation of the purpose and operation, I will proceed to describe the invention as it is embodied, in the present instance, in said hereinbefore mentioned Remington machine.

The frame of the machine includes the usual top plate 1 supporting fixed guide rails 2. The carriage or truck comprises front and rear guide or cross bars 3, united by

end bars 4 and 5. The guide rails 2 and cross bars 3 are oppositely grooved to receive crossed anti-friction rollers 6, by which the carriage is supported in the usual manner to travel from side to side of the machine over the top plate 1.

A cylindrical platen 7 is mounted in the usual manner in a platen frame comprising the rigidly connected end plates 8 and 9; the platen frame being connected to the carriage by the usual shift links 10 and 11. In the present instance, however, I contemplate writing only with upper case characters and the platen is, therefore, preferably held in the upper case position. This may be readily done by screwing up the lowermost case-shift limiting screw-stops 12, thereby holding the platen shaft, or the buffer springs 13 which surround it, against the upper-case limiting stops 14. This brings the printing line on the platen to a position where the uppermost types 15 on the usual type bars 16 will register therewith.

A ribbon vibrator 17 is mounted to slide up and down in the usual manner on a type bar center guide 18 secured to the type bar segment 19. The vibrator is actuated at each printing operation by the usual mechanism (see Fig. 2^a), which includes an arm 20. Said arm is pivoted at 21 on a shiftable carrier or support 22 mounted on parallel links 23. A contractile spring 24 tends to lift the shiftable support 22, and causes an anti-friction roller 25 carried thereby to bear upward against the lower edge of a bar 26. This bar is secured to the carriage and extends substantially throughout the length thereof. In the usual Remington machines the purpose of this construction is to cause the ribbon vibrator to be shifted up and down with the platen in the case shifting movements of the latter. In the present construction there is no such case shifting movements of the platen but the construction, nevertheless, lends itself to the accomplishment of another result which will hereinafter appear.

As in the construction disclosed in said Walsoe patent, it is desirable when introducing a work sheet backwardly into the machine to lower the ribbon vibrator from its normal, Fig. 1, position. This is in order to enable the front paper deflector to be more conveniently moved to effective position, as shown in Fig. 2. In the present construction I have employed the same means that are disclosed in said Walsoe patent for effecting this result. Thus, as in the prior construction, a bracket arm 27 extends forward from the shiftable support 22 and carries an anti-friction roller 28 at the upper end thereof. A rock shaft 29 extends throughout the length of the carriage and is mounted at its ends in bearing openings in the end plates 8 and 9 of the

platen frame. This rock shaft 29 carries a plate 30 which extends substantially throughout the length thereof and is bent down at its forward edge to form a flange 31 which coacts with the anti-friction roller 28. When the rock shaft 29, and the plate 30 carried thereby, are shifted by means to be hereinafter described, from the Fig. 1 to the Fig. 2 position, the shiftable support 22 will be lowered against the power of its spring 24 effecting a corresponding lowering of the ribbon vibrator 17.

Coming now to the means for controlling and guiding the work sheets, it will be observed in the first place that there are no paper feed rollers employed beneath the platen, such rollers as are employed being located above the printing line, leaving the space beneath the platen free for the use of other devices.

There are two curved paper deflectors 32 and 33 employed beneath the platen, one arranged above the other and maintained spaced apart by intermediate spacing members or blocks 34 and 35 located near the ends thereof. Generally speaking, these deflectors conform to the curvature of the platen or are substantially concentric therewith and extend substantially throughout the length of the platen. As thus constructed there are two separate channels provided, one of which is the open channel 36 between the two deflectors and which is bounded at its ends by separating members 34 and 35, either or both of which may constitute side guides or gages for cooperation with a work sheet or sheets introduced into the channel 36. The other separated channel 37 is provided between the under surface of the platen and the upper deflector 32. The forward edge of the deflector 33 terminates in advance of the forward edge of the deflector 32, and has a slight downward curve in cross section. The deflector 33 is continued up at the rear to form an upwardly and rearwardly extending paper table 38 which terminates at a considerable height above the platen. On the other hand, the deflector 32 terminates in the rear of the platen at a much lower point and below the top of the platen, where it is bent to form a loop 39 that loosely surrounds a rod 40 fixedly connected at its ends to the end plates 8 and 9 of the platen frame. In this manner the rigidly united deflectors 32 and 33 are mounted on the rod 40 and have a slight pivotal movement thereon.

A light wire spring 41 is connected by screws 42 and 43 to a cross bar 44 of the platen frame, the spring being anchored at one end on the screw 42 and coiled around the stem of the screw 43. The upper free end of the spring 41 is looped at 45, where it bears upward against the bottom of the deflector 33 and causes the forward edge portion of the de-

5 reflector 32 normally to be lightly pressed against the platen, or against the interposed work sheet. In this manner the sheets introduced from the rear of the platen through
10 the channel 37 will be held snugly against the platen, and the sheets introduced into the channel 36 will be prevented from entering the channel 37. By moving the upper end of the paper table forward, the forward end portions of the deflectors may be moved downward a limited distance, thus carrying the forward contact edge of the reflector 32 away from the platen, as provided for in the construction disclosed in
15 the hereinbefore mentioned Hart Patent 1,650,851. Unless this contact of the reflector 32 with the platen is nicely regulated and controlled, there is apt to be an undue binding of said reflector on the platen, or
20 on the register sheet, during the forward turning of the platen.

I have provided adjustable means for determining the normal position of the double reflector on its pivot 40, and also for determining the limit of pivotal movement that said double reflector may receive away from normal position, which will now be described.

Referring more particularly to Figs. 1, 9
30 and 12, it will be seen that a cross bar or supporting rod 46 is connected at its ends to the end plates 8 and 9 of the platen frame, and is fixed thereto against turning movement. One or more sleeves 47 are mounted
35 on this rod, two being shown in the present instance. Each sleeve is tapped transversely throughout its diameter in two lines at right angles to each other, so as to provide a plurality of tapped openings 48. In the most
40 convenient one of these openings is received a set screw 49 that is adapted to bear at its inner end against the supporting rod 46. Fixed to each sleeve 47 is a snail-cam 50, the curved contact edge of which is adapted
45 to form a bearing against which the back of the paper table 38 is pressed by the spring 41, thus determining the normal position of the double reflector on its pivot and preventing the forward edge of the reflector
50 32 from bearing with undue force against the platen. By a turning adjustment of the cams 50 around their supporting rod, the position of the forward edge portion of the reflector 32 with reference to the platen may
55 be nicely regulated, the screws 49 holding the cams in the positions to which they are adjusted.

In order to limit the pivotal motion of the double reflector in the opposite direction, I
60 provide one or more additional adjustable snail-cams or stop devices 51 to contact with the bottom of the reflector 33, as indicated in Figs. 1 and 6. The carriage of the Remington machine, as manufactured, has on
65 its cross bar 44 a series of faced lugs 52

located near the ends of the bar, each of them being tapped fore-and-aft of the machine. In the present instance I make use of two of these tapped openings to receive the stems of headed binding screws 53. On each of these screws is supported one of the cams 51. By slightly loosening each of the screws 53, the associated cam or stop 51 may receive a turning adjustment around the stem of its screw to bring the curved contact edge of the cam or stop closer to or further from the bottom of the reflector 33, and thus regulate the extent of releasing motion of the double reflector. When the cams 51 are adjusted to the proper position, a tightening of the screws 53 will hold the cams with a binding action in such position.

The above described means for adjusting the double reflector are not claimed herein but are claimed in a division of this case filed Dec. 1, 1927, Sr. No. 236,984.

It is intended at times to introduce rearwardly through the channel 36, first one comparatively heavy ledger sheet L (see Fig. 10), and then a comparatively thin or light statement sheet S. Ordinarily the tendency of the first introduced curved and relatively wider ledger sheet L is to spring or force itself towards the bottom of the channel 36, or against the upper side of the lower reflector 33. It follows therefore that the ledger sheet, under these conditions, will interfere to a certain extent with the subsequent rearward introduction of the statement sheet S between the previously introduced ledger sheet and the reflector 33. This difficulty is more pronounced when the statement sheet is relatively thin, or made from very light stock. In order to overcome this disadvantage I have provided, by the present invention, work sheet supporting means in the channel 36 for supporting the ledger sheet in an unobstructing position in said channel, where it will not interfere with the ready insertion and free passage through the channel of another work sheet, such as the statement sheet, as clearly indicated in Fig. 10. Such means in the present instance comprises a plurality of work-supporting members or ribs 54 carried by and projecting upward from the contact face of the reflector 33, in the channel 36. As shown, there are two of these supporting members or ribs 54, having a parallel arrangement and extending fore-and-aft of the machine through the channel 36 and terminating at 55 near the top of the paper table 38. The thickness of each rib 54 is preferably such that, within its field of operation in the channel 36, it occupies preferably about one-third of the space between the two reflectors 32 and 33. The ribs may be located at appropriate points longitudinally of the platen, and be properly spaced apart, in order to leave an intervening space

between them. Through this intervening space a work sheet S (Fig. 10) may pass free from obstruction through the channel 36, while another work sheet L is supported 5 on the upper contact faces of the ribs 54. I prefer to mount the ribs so that they may be adjusted to different positions longitudinally of the platen, in order that various widths of sheet S may be introduced between 10 said ribs in the channel 36. Any suitable means may be employed for this purpose. In the present instance, I provide three parallel series of openings 56 in the deflector 33 and paper table 38 for each of the ribs. The different series of openings 15 for each rib are spaced apart longitudinally of the platen about three-quarters of an inch. A series of screws 57 pass through a series of openings 56 and are received at their threaded ends in tapped openings in 20 a companion rib, to detachably secure each rib in any one of the three positions to which it may be adjusted along the channel 36. It has been found in practice that the means 25 described effectively overcome the difficulties pointed out above in successively introducing two work sheets in the channel 36.

In order to facilitate the backward introduction of the work sheets into the mouth 30 of the channel 36 from in front of the platen, there is provided a guide, shield, or paper deflector 58 that is movable on the carriage from a substantially horizontally disposed ineffective position, shown in full lines in 35 Fig. 1, to a downwardly and rearwardly inclined effective position, shown in Fig. 2, and vice versa, as disclosed in certain of said hereinbefore mentioned patents. In order to receive these movements the deflector 40 is constructed and mounted, in the present instance, in the specific manner disclosed in said Walsoe Patent 1,663,362.

Thus, the sheet metal deflector 58, which extends substantially throughout the length 45 of the platen, is bent under along one-edge portion to form a looped or doubled portion 59, which extends throughout its length on the side thereof opposite its contact face forming an enclosed channel within the 50 looped portion. In the open ends of the channel formed by the looped portion of the deflector are received oppositely directed ears or bent ends 60, which project inwardly from parallel sheet metal supporting arms 61 and 62 and are riveted to the deflector 58. These supporting arms 61 and 62 are pivotally mounted respectively on forwardly projecting arms 8^a and 9^a secured to the end plates 8 and 9 respectively 55 of the platen frame and which may be regarded as parts of said end plates.

The arm 62 is loosely supported on an inwardly projecting shouldered pin 63 secured to the end plate 9 (see Fig. 6) and 60 has a sliding, as well as a pivotal movement

on said pin. A coiled expansion spring 64 surrounds said pin and tends to force the arm 62 and the parts connected therewith to the left, for purposes which will presently appear. The arm 61 is supported 70 on the shouldered bearing portion of a headed pivot screw 65, as shown in Fig. 6, for pivotal movement and also for axial movement along said pivot screw. The threaded end of this screw is received in a tapped opening in the end of a shouldered pin 66 secured to and projecting inward from the end plate 8 of the platen frame. Loosely supported on this same pin 66, intermediate a shoulder thereon and the end of 75 the shouldered portion of the screw 65, is a hub 67 to which is riveted an actuating arm 68. The hub 67 and connected actuating arm 68 are therefore free to turn on the supporting pin 66 but are held against axial 80 movement thereon. An inwardly projecting pin 69 is secured to the arm 68 and has a reduced portion 70 at the end thereof. This reduced end fits in an opening in the supporting arm 61 of the deflector 58. This 85 connection between the arms 61 and 68 causes them to turn together and is normally maintained by the force exerted by the spring 64. The construction is such, however, that the deflector 58 may be shifted 90 to the right on its pivotal supports 63 and 65 against the force of the spring 64. At this time the connection between the arms 61 and 68 will be broken and the deflector 95 100 105 110 115 120 125 130 58 is free to drop forward and downward until arrested by the top plate 1, as shown in dotted lines in Fig. 1. The main purpose of thus disconnecting the deflector 58 from its actuating arm 61 and the means by which the latter is controlled, and moving the deflector to the dotted line Fig. 1 position, is to give access to the ribbon vibrator 17 for threading the ribbon 17^a therethrough.

The arm 68 constitutes one arm of a bell crank lever, the other arm of which is indicated by the reference numeral 71. The arm 71 carries an outwardly projecting connecting pin 72 that is received and works in a slotted cam 73 in an actuating arm 74. Said arm 74 is provided with a hub 75 (see Fig. 6) by which it is secured to the hereinafter mentioned rock shaft 29. The character of the slotted cam and the construction and the arrangement of the parts are such that a forward pivotal movement of the arm 74 from the Fig. 1 to the Fig. 2 position, causes a pivotal movement of the deflector 58 in the opposite direction, or rearwardly from its normally ineffective position. This brings the deflector 58 to the effective position, shown in Fig. 2, where it overlaps and virtually forms a continuation of the deflector 33. In this movement of the deflector 58 it passes from a position where it is out of

- the path of the type bars to a position where it is in the path thereof, and crosses the printing line where it is effective in directing work sheets introduced rearward 5 from in front of the platen downward into the open channel 36. From thence the sheets in question pass around and beneath the platen to the rear thereof.

The actuating arm 74 is provided with a 10 finger piece 76 at the upper end thereof, whereby said arm and the parts controlled thereby may be actuated at will. The arm 74 also stands in cooperative relationship with means for controlling the shifting 15 movement of certain of the feed rollers, to be automatically controlled thereby, as will hereinafter clearly appear.

The actuating arm 74 constitutes one of two supporting arms for a wire line-indicator 77. Said indicator extends longitudinally throughout the length of the platen and is adjustably connected to the arm 74 by novel means of the present invention which will now be described.

25 The arm 74 is formed with a lug 78 that extends in a plane at right angles to the plane of said arm, as indicated in Fig. 7. This lug constitutes one jaw of a clamp, a plate 79 constituting the other jaw of said clamp. A pair of headed screws 80 have their stems extending freely through openings in the clamping jaws 78 and 79 and engage tapped openings in a plate 81 in the rear of the plate 79. One end of the wire line indicator 77 passes between the clamping jaws 78 and 79 intermediate the screws 80, and may be adjusted up and down between the contact faces of said jaws. By tightening the screws 80, the clamping jaw 79 will be drawn towards the jaw 78 and firmly clamped and hold the wire 77 in its adjusted position on the arm 74. One distinct advantage of this form of adjusting means is that it enables the assembler to grasp, with a pair of pliers, the projecting end of the wire 77, shown in Fig. 7, and draw the wire taut throughout its length. By then bending the wire over a corner of the jaw 78, as shown, the wire will be prevented from relaxing from its taut condition while it is being adjusted up or down at this end of the arm 74, and while the screws 80 are being tightened to firmly hold the wire in its adjusted position.

50 I also prefer to provide a stop 79^a off-set from the plate 79 and which coacts with a stop pin 82 (Fig. 1) that projects inward from the end plate 8 of the platen frame, and thus limits the rearward movement of 55 the arm 74 and the parts controlled thereby. This method of limiting the movement of the parts is superior to the provision of a stop to coact with the platen for this purpose, since in the present construction the stops do not interfere with a register sheet,

for example, reaching to or extending beyond the ends of the platen.

The opposite end of the line indicating wire may be secured to a vertically adjustable slotted plate 83 (see Fig. 3) held by 70 screws 84 on a second supporting arm 85, as disclosed in said Walsoe patent. The arm 85 is secured to the rock shaft 29 near the right-hand end thereof. A coiled contractile spring 86 is connected at one end to the arm 74 and at its opposite end to a pin 87 extending inward from the end plate 8. This spring tends to return the arm 74 and the parts connected therewith to the 75 normal, Fig. 1, position where the arm is 80 arrested by the cooperation of the stops 79^a and 82.

The novel features above described for adjustably mounting the line indicating wire 77 and for arresting its movement towards 85 the platen etc., are not claimed herein but are claimed in a division of this application filed Dec. 13th, 1927, Sr. No. 239,706 (now Patent No. 1,752,484).

The paper feeding mechanism embodied 80 in the present construction includes a plurality of aligned paper feed rollers 88, arranged to coact with the top of the platen and with work sheets introduced from the rear of the platen through the channel 37. Said feed rollers 88 coact with said sheets after the latter have passed above and beyond the printing line. The paper feed rollers 88, as shown in the present instance, are constructed and mounted in the same general manner as in said hereinbefore mentioned Hart Patent 1,650,351, except for changes in mounting the spindle on which said feed rollers turn, as will presently appear. Thus, the feed rollers are mounted 85 for longitudinal adjustment along a supporting rod or spindle 89, supported at its ends by forwardly extending arms 90 that are pivoted on the supporting rod 46, hereinbefore referred to, which is secured at its ends 90 to the platen frame. Springs 91 exert their force against the arms 90 and thus cause the feed rollers 88 to bear against the platen, or certain only of the work sheets thereon. By swinging the bail 89 upward and rearward the said feed rollers are released.

I provide each of the arms 90 with an inwardly projecting bearing member 92, shown in detail in Figs. 13 and 14, in which the ends of the spindle 89 are loosely seated, 120 as shown, the diameter of the bore of each bearing being greater than the diameter of the spindle. This is in order that there may be an equalization of pressure exerted from the individually acting springs 91 on opposite ends of the roller supporting spindle 89. Although it is desirable to thus loosely support the spindle 89 at opposite ends so that said spindle may assume varying angular relations relatively to the axis of the 125 130

platens as well as a parallel relation thereto, it also is desirable to prevent or limit the turning movement of the spindle in its bearings. This is preferred because, among 5 other reasons, I mount side edge paper gages on the spindle 89, as will presently appear, and any material turning of the spindle which would displace said gages from effective position should be prevented. Therefore, I provide each end portion of the spindle with a cross pin 93 projecting from opposite sides of the spindle into slots 94 extending longitudinally of the companion bearing member 92 and through the walls 10 thereof. The diameter of each pin is preferably slightly less than the width of the slot 94 in which it is received. This construction affords a slight relative pivotal movement between the arms 90 so that there 15 may be an equalization of pressure of the springs 91 on the feed rollers 88 at the opposite ends of the spindle 99. The extent of this slight relative movement between the arms 90 is determined by the extent of lost 20 motion of the pins 93 in their respective slots 94. When shifting the feed rollers 88 away from the platen the arms 90 will shift in unison when the slight extent of lost motion of the pins 93 in their slots 94 is taken 25 up. Each bearing member 92 may be secured to its companion arm 90 by any suitable means. In the present instance each bearing member has a threaded extension or 30 stud 95 which passes through an opening in the companion arm 90 and engages a nut 96 on the opposite side thereof.

The above described means for mounting the spindle 89 are not claimed herein but are claimed in my divisional application Sr. No. 10 236,984 hereinbefore referred to.

In the present construction I have provided means for automatically locking the feed rollers 88 in ineffective position when they are thrown off. Referring more particularly to Fig. 1, it will be seen that the left-hand arm 90 carries an outwardly projecting headed pin 97. The stem of this pin passes through a curved slot 98 in a locking member or latch 99, pivoted on a 5 headed pivot screw 100 threaded into a tapped opening in the end plate 8. The curvature of the slot 98, when the latch is in the full-line position, is substantially concentric with the axis of the rod 46 on which 10 the arms 90 turn. Extending at an angle to the slot 98 at the upper end thereof is a locking notch 101 that provides a locking shoulder 102. A leaf spring 103 is secured 15 at one end by a screw 104 to the end plate 8, whereas the free end of said spring extends beneath a shoulder 105 on the latch 99. The force of this spring is exerted to 20 shift the latch from the full to the dotted line position when the left-hand arm 90 is 25 shifted to the dotted line position to release

the feed rollers 88. The effect of this movement of the pivoted latch to the dotted line position is to bring the locking shoulder 102 beneath the pin 97, and positively hold the feed rollers 88 in the released position 70 against the action of their springs 91. The latch 99 terminates at its upper end in a finger piece 106 by which the latch may be swung forward from the dotted to the full-line position, thereby releasing the pin 97 and enabling the feed rollers to be returned to normal position by their springs 75 91.

The automatically operating latching means described above leaves both hands of the operator free to adjust the register sheet and its accompanying carbon sheet when the feed rollers 88 are released.

In the present construction I have provided two independent side edge gages 107 and 108 which are mounted on the supporting rod or spindle 89, as shown in Figs. 1, 4 and 6. Each gage is fixed on an independent hub or carrier 109, tapped to receive a set screw 110 by which it is held in any position to which it may be adjusted along the spindle 89 on which it is mounted. The gage 107 projects rearward from the supporting spindle for cooperation with the left-hand side edge of a work sheet introduced into 95 the channel 37 from the rear of the platen, whereas the gage 108 extends forward from the spindle where it coacts with the left-hand side edge of a work sheet introduced 100 from in front of the platen in the channel 36. The spindle 89 being fixed against appreciable turning movement in the arms 90, will hold the gages from unduly turning around the axis of said spindle, when the 105 gages are held in place by the set screws 110. Nevertheless, the gages swing with the spindle when the latter is turned with the arms 90 around the axis of the supporting rod 46 to releasing position. It will be 110 understood that by making the gages 107 and 108 relatively adjustable they may be adjusted one with reference to the other, as well as affording an adjustment of both of them to various points along the spindle while a given space between them is maintained. Moreover, it will be seen that each gage is reversible on the supporting spindle, so that the gages may be arranged with their hubs extending toward each other, as 115 shown, or one extending outward to the left, or both extending inward to the right, or where the gages are to be brought in close relationship the hubs may extend away from each other, giving the closest possible 120 arrangement of the plate-like gages 107, 108.

The above described side edge gages 107 and 108 and the means for mounting them are not claimed herein but are claimed in 130

my said divisional application Sr. No. 236,984.

Aside from the side edge paper gages described above, it should be understood that 5 suitable paper end stops, such, for example, as certain of the end stops described in said hereinbefore mentioned patent to Burns # 1,647,854, may be employed. However, 10 since a specific description of such end stops 10 is unnecessary to arrive at an understanding of the present invention, further detail reference thereto will be omitted.

In the present machine I have included 15 certain features of the paper feed roller controlling means disclosed in said Walsoe application, as well as the means by which the paper deflector 58, line indicator 77 and ribbon vibrator 17 are automatically controlled thereby. In some instances I have modified 20 such mechanism, and in other instances I have combined therewith new features for converting the machine into a so-called three-sheet biller, as will now be described.

A plurality of aligned paper feed rollers 25 111, preferably two in number and in the nature of margin feed rollers, are mounted for adjustment along a supporting rod, carrier, bar or spindle 112. Any suitable means may be employed to retain said rollers 30 in their adjusted position along the spindle 112, such for example, as the means disclosed in the said Walsoe & Hill patent. The spindle 112 is reduced at its ends where it is provided with circumferential grooves 35 113 (Fig. 5), in each of which is received parallel guide members 114 of a supporting arm or guide. The left-hand supporting arm 115 at its front end is secured by a screw 116 to the carriage. The rear end 40 portion of said arm is adjustably connected to the upper end of a supporting link 117, the lower end of which is supported on the inwardly projecting pin 66 on the platen frame. From an inspection of Fig. 2 it 45 will be seen that one side of this pin is cut away at 66^a to provide a clearance for that part of the arm 74 in which the cam slot 73 is formed. The means of my present invention by which an up and down adjustment 50 of the arm 115 on the link 117 is effected, is best shown in Fig. 11, although any suitable means may be employed for effecting this adjustment. From this figure it will 55 be understood that an eccentric 118 is loosely seated in an opening 119 in the link 117. This eccentric has a hexagonal head 120 by which it may be turned. An eccentrically arranged opening 121 through the eccentric receives the stem of a headed binding screw 60 122. The threaded end of this screw engages in a tapped opening 122^a in the supporting arm 115. When the screws 122 and 122^a are loosened, the eccentric 118 may be turned, thus effecting a slight up or down 65 adjustment of the rear end of the support-

ing and guide arm 115 around the point of its connection 116 with the carriage. By tightening the screws 116 and 122 the arm may be held fixed in its adjusted position. The effect and purpose of this adjustment 70 of the arm 115 will be hereinafter made clear. A second corresponding supporting and guide arm 123 is provided for the opposite end of the spindle 112. Said arm 123 is connected at its forward end by a screw 75 with the carriage, and is adjustably connected at the rear end to a link 124 in the manner previously described in connection with the arm 115. The lower end of this link 124 is supported on the inwardly projecting pin 63, as shown in Fig. 6, and constitutes an abutment for the outer end of the spring 64 to bear against. The arm 123 supports and guides the spindle 112 in the same manner as the arm 115, for rectilinear 80 bodily movement fore and aft of the machine above the printing line, to move the feed rollers 111 in a like manner from the effective, Fig. 1, position, to the ineffective, Fig. 2, position, and vice versa. 85

In order to control the above described movements of the feed rollers 111 there is provided a rock shaft 125 mounted at its ends in bearing openings in the arms 115 and 123. Two parallel crank arms 126 and 127 have their hubs 128 and 129, respectively, secured to the rock shaft 125 to cause said arms to rock with the shaft from the Fig. 1 to the Fig. 2 position, and vice versa. The arm 126 has an upwardly 90 extending projection 130 that terminates in a finger piece 131 by which the rock shaft 125 and the parts connected therewith may be controlled. Each of the arms 126 and 127 is in the nature of a toggle 95 arm or member, the arm 126 being pivoted at 132 to the forward end of its companion toggle link or member 133. The rear end of the toggle link 133 is apertured to receive the spindle 112. A collar 134 100 (Fig. 4) is detachably secured on said spindle at one side of the link 133, whereas the spindle carries a washer 135 on the opposite side of said link, interposed between the link and the arm 115. The other 105 toggle arm 127 is connected in a like manner with a toggle link 136, which in turn is connected with the spindle 112 in the same manner as the link 133, and the same reference numerals are employed to designate the corresponding parts of such connections. Laterally projecting pins 137 and 138 (see Fig. 8) are carried by the toggle members 127 and 136 respectively, and to these pins are connected the opposite ends 120 of a contractile spring 139. The construction and arrangement of the parts are such that when they are disposed as indicated in Fig. 1, the spring 139 exerts substantially a dead-center pull against the sub- 125 130

stantially dead-centered toggle members and is ineffective to withdraw the paper feed rollers 111 from contact with the platen or a work sheet thereon. When, however, a 5 forward pressure is exerted by the operator on the finger piece 131 to break the toggles said spring 139 exerts its force effectively and tends to complete the withdrawal of the feed rollers 111 to ineffective position, indicated in Fig. 2. On the other hand, 10 when the operator moves the finger piece back from the Fig. 2 position, to the position indicated in Fig. 1, this results in straightening the toggles at both ends of 15 the spindle 112 and applying the feed rollers 111 with a positively exerted force against the platen, or a work sheet thereon. The toggle 126 and 133 is limited in this movement by the stop lug 140 which 20 projects from the arm 115 into the path of the toggle arm 126. The toggle arm 127 also is limited in its movement by a corresponding stop lug projecting inward from the supporting arm 123.

25 I have referred to moving the toggle members to a substantially straight line position when applying the feed rollers 111. In practice it is preferable when thus moving said feed rollers to arrest the toggle members after they have passed slightly over the straight line or dead-centered position, so as to hold the feed rollers 111 applied and prevent the reaction of the parts from accidentally releasing said feed rollers. 30 They will thus be retained applied indefinitely, or until such time as the operator manually effects a preliminary breaking of the toggle from the Fig. 1 position, and enables the spring 139 to exert a force 35 which tends to complete the movement of the feed rollers to ineffective position.

In accordance with my present invention I provide an additional, or secondary set of paper feed rollers, preferably two in 40 number, and auxiliary means for controlling said feed rollers, so that they may be employed in conjunction with what may be termed the primary feed rollers disclosed in said Walsoe application to act as 45 a so-called three-sheet biller. This mechanism will now be described.

As shown in the present instance, a set 50 of two aligned auxiliary or secondary feed rollers 141 are mounted on a spindle 142 carried by a sheet metal yoke or supplemental carrier 143. The vertically disposed end arms 144 and 145 of this yoke are apertured at 146 (see Fig. 8) to provide bearing openings in which the spindle or main carrier 55 112 is received and on which spindle the yoke is carried for bodily movement therewith and for independent pivotal movement thereon. This construction is such that 60 when the primary feed rollers 111 are in 65 the effective (Fig. 1) position, a shifting

of the yoke 143 from the dotted to the full-line position in said figure will carry the secondary feed rollers 141 into contact with the platen, or with, say, a statement sheet on the platen introduced rearwardly into the channel 36 from the front of the platen. While, as indicated above, the feed rollers 141 move bodily towards and away from the platen with the supporting rod or spindle 112, they are out of axial alignment 70 with the rollers 111 and it is the pivotal movement of the feed rollers 141 around said supporting spindle or main carrier which determines whether the feed rollers 141 are effective or ineffective, even though the spindle 112 be in the advanced Fig. 1 position. The means by which the pivotal position of the feed rollers 141 around the spindle 112 is determined are as follows:

Referring more particularly to Fig. 8, it 75 will be seen that an off-set ear 147 is provided on the upright arm 144 of the yoke or carrier 143. A headed pivot pin 148 connects said ear to a link-like controlling or locking member 149. An upwardly extending arm 150 on the member 149 terminates in a finger piece 151, by which said member and the parts controlled thereby may be manipulated in a manner which will presently appear. The forward end of the member 149 has a slot therein having a portion 152 thereof at one elevation and a portion 153 at a higher elevation. The formation of the slot is such that a locking shoulder 154 is provided intermediate the two 80 portions 152 and 153 of the slot. A headed pin 155 extends through said slot and is carried, in the present instance, on a crank arm 156 fixed on the rock shaft 125. A laterally projecting pin 157 on the member 149 is connected to one end of a contractile 85 spring 158, the other end of said spring being connected to the yoke 143. The power of this spring is exerted to turn the yoke 143 from the dotted to the full-line position 90 in Fig. 1, and apply the feed rollers 141 to the platen. The power of the spring 158 also tends to turn the forward end of the link 149 downward when the parts assume 95 the relation shown in Fig. 8. The manner 100 in which the feed rollers 141 and the controlling means therefor function, will now be described.

Assume that a register sheet R (Fig. 10) 105 and its accompanying carbon sheet (not shown) have been introduced through the channel 37 and properly positioned with the leading edges thereof beneath their feed rollers 88, and that the remaining parts are in the Fig. 2 position. The operator then 110 introduces a ledger sheet L from the front of the platen into the channel 36 and accurately positions said sheet. An actuation 115 of the finger piece 131 in a direction opposite to that indicated by the finger thereon 120

in Fig. 2, results in straightening the toggles to the Fig. 1 position and positively applying the feed rollers 111 against the platen and against the margins of the previously introduced ledger sheet. At this time the finger piece 131 and the parts controlled thereby are in the dotted-line, Fig. 1, position, with the feed rollers 141 in the released position. This is due to the fact 10 at this time the locking shoulder 154 engages the pin 155 and holds the yoke 143 against the force of the spring 158, as indicated in dotted lines in Fig. 1. The statement sheet S with an accompanying carbon 15 sheet (the latter not being shown) may then be introduced from the front of the platen into the channel 36, and between the feed rollers 141 and the platen, or the ledger sheet thereon. After the statement sheet 20 and the accompanying carbon sheet have been properly adjusted, the finger piece 131 is shifted by the operator from the dotted to the full-line Fig. 1 position. This results in first moving the forward end of the 25 link or member 149 up disengaging the locking shoulder 154 from the pin 155. The spring 158 is then effective to swing the yoke 143 and feed rollers 141 from the dotted to the full-line Fig. 1 position, thereby 30 applying said feed rollers to the previously 35 adjusted statement sheet S. The machine is then conditioned to proceed with the writing, and the matter written will be produced on the statement sheet and 40 through the carbon sheets on the ledger and register sheets.

After the "statement" is written as described, the operator shifts the finger piece 131 to the Fig. 2 position, thereby releasing the feed rollers 111 and 141 and permitting ready withdrawal of the statement sheet, the accompanying carbon sheet and the ledger sheet, and conditioning the machine for new sheets to replace those withdrawn. It will 45 be seen that the act of shifting the parts as last described, with the aid of the finger piece 131, resulted in automatically dropping the front end of the link from the position where the locking shoulder 154 is 50 released from the pin 155 (see full lines in Fig. 1), to the position where said shoulder is positioned to engage said pin, as shown in Fig. 2. The effect of this was to automatically condition or lock the feed rollers 141 so 55 that they will not be applied to the platen or a work sheet thereon when the next, or any subsequent, actuation of the finger piece 131 is effected to apply the feed rollers 111 to the ledger sheet. In fact the feed rollers 60 141 are thus automatically conditioned or locked out of effective position indefinitely, or until they are again applied by an independent actuation of the finger piece 151 in the manner hereinbefore described. This 65 occurs after a new ledger sheet has been in-

serted, positioned, and clamped in position by its feed rollers 111, and after a new statement sheet and accompanying carbon sheet have been introduced and positioned in place. After each writing of a statement and ledger sheet as described, the automatically operating locking means for the feed rollers 141 will function during the act of shifting the finger piece 131 from the Fig. 1 to the Fig. 2 position, and can only be released by an independent actuation of the finger piece 151.

I have shown and described the locking link or member 149 as supported on a pin 155 carried by a crank arm 156 on the rock shaft 125, simply because the provision of the crank arm constitutes a convenient place to support the pin 155. The locking link is moved fore-and-aft of the machine by reason of its connection with the spindle 112, so that there is no necessity for the provision of a movable pin 155, and it may therefore be mounted on any convenient part of the carriage, and the devices will function in the manner described.

By providing the feed rollers 141 and the controlling means therefor, I convert the so-called two-sheet biller described in the hereinbefore mentioned Walsoe application into a so-called three-sheet biller.

It will be understood, moreover, that the spindle 112 and the rock shaft 125 are detachable from the machine with little difficulty, and that the feed rollers 141 and the means for controlling them may be readily attached to or detached from the rock shaft 125 and the spindle 112. Therefore, these devices are in the nature of an attachment which may be applied or omitted at will, depending on the use to which the machine is to be put, as a two-sheet or three-sheet biller. It will be understood, moreover, that in applying the attachment to the machine disclosed in the Walsoe patent, it is unnecessary to modify the structural features existing in 100 said machine.

It has been hereinbefore pointed out that by the adjusting means disclosed in Fig. 11 for the guide arms 115 and 123, the positively applied feed rollers 111 will be pressed with more or less force each time they are applied, depending on said adjustment. It is believed that this will be readily understood since said feed rollers are applied above the printing line, and the adjustment of the guide arms is transverse to the line of rectilinear movement of said feed rollers 111 into effective position and slightly changes such path of movement relatively to the inclined contact face of the platen. Therefore, the downward adjustment of the guide arms will bring the feed rollers 111 nearer to the platen, so that they will be applied with greater force when the actuating toggles are straightened. On the other 130

hand, an upward adjustment of the guide arms carries the feed rollers 111 further from the platen, so that they will be positively applied with less force when the 5 toggles are straightened.

Thus far I have described the means for moving the feed rollers 111 into and out of contact with the platen without reference to the automatic control by such means of 10 the line-indicator 77, the paper deflector 58 and the ribbon vibrator 17. The arrangement by which such automatic control is effected is to extend the actuating arm 74 into the path of the bodily movable spindle 112. 15 Thus, it will be seen that said actuating arm extends up between the supporting arm 115 and the toggle link 133. As the parts move from the Fig. 1, to the Fig. 2 position, the washer 135 on the left-hand end of the 20 spindle 112 will coat (after a preliminary extent of lost motion) with the actuating arm 74. This will result in automatically shifting the line indicator 77 to ineffective position, in shifting the deflector 58 to effective position and in lowering the ribbon 25 vibrator 17 out of the path of the said deflector, all as represented in Fig. 2. Such movements of the parts in question will have been effected by the time the stop projection 159 30 on the lever 74 reaches the coacting stop 140, as shown in Fig. 2, and arrests further movement of the parts.

It will be seen that while the parts referred to above are automatically actuated during the withdrawal of the feed rollers 111 from effective position, nevertheless by an actuation of the finger piece 76, the line indicator 77, deflector 58 and the ribbon vibrator 17 may be moved independently of the 40 feed rollers 111 from the Fig. 1 to the Fig. 2 positions, and while said feed rollers remain applied to the platen.

At different times, depending on conditions of use of the machine, it is required 45 that the deflector 58, line indicator 77, and ribbon vibrator 17 be automatically moved to their respective positions when the feed rollers 111 and 141 are moved bodily back and forth between the Fig. 1 and the Fig. 2 50 positions, and that said deflector, line indicator and ribbon vibrator be independently controlled by the finger piece 76, as explained above. But it is also essential at times that said feed rollers be released without 55 moving the line indicator from its effective position, as indicated in Fig. 3. This is necessary when for example the line indicator is to be wholly relied upon to effect proper adjustments in a line feed direction, 60 of the sheets (such as the ledger sheet L and statement sheet S) introduced rearwardly in the channel 36. To attain these ends the provision of lost motion between the left-hand washer 135 (on the spindle 112) and 65 the arm 74 enables the rollers 111 and 141

to be moved from the full-line Fig. 1 position, to that indicated in Fig. 3, without moving the line indicator 77 from its indicating position, and without disturbing the deflector 58 and the ribbon vibrator 17. 70 Therefore, at this time the ledger sheet beneath the rollers 111, and the subsequently introduced statement sheet beneath the feed rollers 141, may each be separately adjusted with reference to the line indicator 77. 75

In order that the feed rollers 111 and 141 may be automatically held in, and not be accidentally moved forward beyond the Fig. 3 position by the spring 139, which tends to move said rollers to the fully released, Fig. 80 2 position, I provide a detent means which will now be described:

In the present instance I have provided a simple form of detenting means comprising a comparatively heavy leaf-spring 160 85 which is bifurcated at its forward end, as indicated at 161, to straddle the rock shaft 125. This spring is slotted at 162 to receive the stem of a headed clamping screw 163, received at its threaded end in the supporting arm 115. In this manner the spring may be mounted on said arm 115 for fore-and-aft adjustment. A tightening of the screw will bind the spring in its adjusted position at the anchored end thereof. The 90 rear free end portion of the spring is bent, as clearly shown in Fig. 5, to provide an inclined detent face 164 with which the left-hand end of the spindle 112 coacts, as shown in dotted lines in the above mentioned figure, 100 when the parts attain the Fig. 3 position. It will be understood that the power of the spring 160 is such as to overcome the tendency of the spring 139 to move the feed rollers to the Fig. 2 position. Therefore, the 105 operator may break the toggles from the straight-line Fig. 1 position, and the parts may be arrested in the intermediate Fig. 3 position, unless it is desired to move them to the Fig. 2 position, where the feed rollers 110 are arrested at the limit of their releasing movement, after the deflector 58, line indicator 77 and vibrator 17 have been shifted. In this event it is merely necessary for the operator to exert a slight pressure on the 115 finger piece 131 after the detent face 164 is reached, which will result in deflecting the detent to one side and enable the shiftable parts to complete their movements to the Fig. 2 position. 120

From an inspection of Fig. 5 it will be seen that a second inclined detent face 165 is provided on the spring 160. The position of this face is such that it will coact with the left-hand end of the spindle 112, on the 125 opposite side thereof from that with which the detent face 164 coacts, when said spindle has completed its releasing movement, and the parts are in the position shown in Fig. 2. The purpose of this detent face 165 is to 130

assure the maintenance of the parts in the Fig. 2 position, or prevent them under the reaction of the spring 86, or otherwise, from being accidentally displaced from said Fig. 5 2 position. This detent face 165 therefore prevents an accidental movement of the deflector 58, line indicator 77 and the ribbon vibrator 17 from the positions which they occupy in Fig. 2 to, say, the Fig. 1 position. 10 Should the deflector 58 thus accidentally move from the Fig. 2 to the Fig. 1 position, it would interpose itself in the path of the type bars and prevent the operator from operating the machine to produce writing. 15 Moreover, the line indicator would be moved to ineffective position and the ribbon vibrator would be lowered. It will, of course, be understood that resistance offered by the detent face 165 may be readily overcome by 20 actuating the finger piece 131 to move it and the parts controlled thereby from the Fig. 2 to the Fig. 1 position.

The means that enable the spring 160 to be adjusted as described, allows the detent 25 faces 164 and 165 to be properly set to coact with the spindle 112 in the different positions specified.

One example of the use of the present machine, such as has been hereinbefore referred to, is as follows:

A register sheet, which is to take the accumulation of the various "statements" to be written, and a corresponding carbon sheet (having its effective face next to the register 35 sheet) are first introduced together from the rear of the platen through the channel 37, being positioned widthwise with the aid, say, of the side edge gage 107. At this time the parts may be disposed as indicated in 40 Fig. 2. The leading ends of the register and its carbon sheet are then introduced beneath the paper feed rollers 88 and the sheets are adjusted to proper position in a line feed direction, if necessary, with the aid 45 of the line indicator 77. This may be readily accomplished by moving the finger piece 131 rearward until the line indicator is in indicating position, which is attained before the feed rollers 111 are moved all of the 50 way to ineffective position, and when the parts have attained the Fig. 3 position. After initially positioning the register sheet in the manner indicated, no further attention need be paid to it in the successive 55 introduction, writing and withdrawal of the different statement and ledger sheets. The register and associate carbon sheet having been initially positioned as indicated, a ledger sheet carrying the account of the 60 "statement" to be written is introduced from in front of the platen through the channel 36, the parts being first positioned, as indicated in Fig. 2, to facilitate the introduction of the ledger sheet. The ledger sheet thus 65 introduced may be properly positioned

widthwise of the machine and the register sheet, with the aid of the side edge gage 108. With the parts shifted to the Fig. 3 position, the line indicator may be employed to locate the ledger sheet in a line space 70 direction. The finger piece 131 is then actuated to straighten the toggles, as shown in Fig. 1, and apply the feed rollers 111 to the adjusted ledger sheet, leaving the feed rollers 141 released, as shown in dotted lines. 75 The finger piece 76 may then be actuated to condition the machine to receive the statement sheet. Pressure is maintained on the key 76 until a statement sheet is introduced rearwardly into the channel 36. 80 When thus positioned the finger piece 76 is released and the statement sheet adjusted with reference to the now effective line indicator 77. The finger piece 151 is now actuated to release the feed rollers 141 from control of the locking means therefor and enable them to bear on the statement sheet and hold it in its adjusted position. The operator may now proceed to write the "statement" and simultaneously produce a manifold copy thereof in requisite positions on the ledger and register sheets. The finger piece 131 is then shifted to the Fig. 2 position and new ledger and statement sheets are 85 introduced, as before. In shifting the parts to the Fig. 2 position the locking link 149 is automatically locked on the pin 155, so that when the feed rollers 111 are next pressed against a newly introduced ledger sheet the rollers 141 will be held in ineffective position and cannot be moved from such position until the finger piece 151 is actuated to release the locking link 149 from its cooperating pin 155. This does not occur until a new statement sheet has been introduced and adjusted, as previously pointed out.

When using the machine for writing comparatively short bill sheets, where entries are always begun at a given point on each sheet, end stops, such for example as disclosed in the hereinbefore mentioned Burns patent, may be employed instead of at all times relying on the line indicator to position the ledger sheet and the bill, statement or invoice sheet. In such event the operation will be much the same as described above, except that it is unnecessary to manipulate the mechanism as described to bring, by a separate operation, the line indicator into use with the ledger and bill sheets. It will be understood that after writing each "statement" the carriage is automatically returned and the platen automatically line spaced, thereby spacing the platen to bring the register sheet in proper position to receive a manifold copy of the next "statement" written on the machine.

In substantially the same manner as that indicated above, the machine may be em-

ployed as a check-writing machine, at which time the sheet described above as a "register sheet" would constitute a manifold record of the checks written and may constitute a 5 "pay roll sheet". In this event, however, no ledger sheet will be employed. The feed rollers 111 will be employed to coact with the checks, and the finger piece 151 would not be manipulated, leaving the feed rollers 141 10 ineffective.

Generally speaking, the sheet described above as a "register sheet", and which remains in the machine when the other sheets are removed and new ones inserted, may 15 constitute a "register sheet", a "proof sheet", a "sales sheet", a "distributing sheet", or a "pay roll sheet", depending on the use of the machine for different purposes.

In some instances the line indicator may 20 be employed to position, in a line feed direction, each sheet introduced from in front of the platen into the channel 36 when it is not feasible or desirable, for one reason or another, to employ end stops. In such 25 an event the machine may be manipulated as hereinbefore described.

By the present invention I have provided a construction which has proved rapid of 30 operation, highly efficient and reliable in use, which is compact and comparatively simple in construction and can be manufactured at comparatively small cost and be readily embodied in existing Remington machines without modifying, or materially modifying, 35 the existing structural features of said machines.

Various changes may be made in the construction and certain parts thereof may be employed without others, without departing 40 from my invention as it is defined in the accompanying claims.

What I claim as new and desire to secure by Letters Patent, is:—

1. In a typewriting machine, the combination of a platen, a set of margin paper feed rollers, controlling means for applying said feed rollers against the platen with a positive pressure, a second set of margin paper feed rollers spring-pressed against the platen, and means rendered effective by said controlling means for restraining the spring pressed rollers against the action of their spring means and away from the platen while the first mentioned set of rollers are being positively applied.

2. In a typewriting machine, the combination of a platen, a set of margin paper feed rollers, controlling means for applying said feed rollers against the platen with a positive pressure, a second set of margin paper feed rollers spring-pressed against the platen, means rendered effective by said controlling means for restraining the spring-pressed rollers against the action of their spring means and away from the platen

while the first mentioned set of rollers are being positively applied, and means for freeing said second set of rollers from said restraining means.

3. In a typewriting machine and billing mechanism therefor, the combination of a platen, a set of margin paper feed rollers, means for controlling the movement of said feed rollers into and out of contact with the platen, a second set of paper feed rollers restricted to a field of operation intermediate said margin feed rollers, independent means operable at will for moving said second set of feed rollers into contact with the platen after the first mentioned set of feed rollers has been applied, and means controlled by the movement of said first set of rollers away from the platen for automatically rendering and maintaining indefinitely the second set of feed rollers ineffective on the platen so that when the feed rollers of the first set are again applied to the platen the rollers of the second set remain ineffective.

4. In a typewriting machine and billing mechanism therefor, the combination of a platen, two sets of paper feed rollers, the rollers of one set being margin feed rollers and the rollers of the other set being restricted to a field of operation intermediate the margin feed rollers, independently operable hand controlled means for effecting an application of the feed rollers of one set to the platen independently of the feed rollers of the other set, and automatically operating means for releasing the feed rollers of one set from the platen when the feed rollers of the other set are released.

5. In a typewriting machine and billing mechanism therefor, the combination of a platen, a set of margin paper feed rollers, means including a finger piece for controlling the movement of said feed rollers into and out of contact with the platen, a second set of paper feed rollers restricted to a field of operation intermediate said margin feed rollers, means including a second finger piece by which the feed rollers of the second set are independently controlled in their movement into contact with the platen after the rollers of the first set are in contact with the platen, and automatically operating means by which rollers of the second set are moved out of contact with the platen when the feed rollers of the first set are withdrawn from the platen.

6. In a typewriting machine and billing mechanism therefor, the combination of a platen, two sets of paper feed rollers, the rollers of one set being margin feed rollers and the rollers of the other set being restricted to a field of operation intermediate the margin feed rollers, a finger piece, means controlled thereby for controlling the movement of both sets of feed rollers towards

and away from the platen, a separate finger piece, means controlled thereby for independently controlling the movement of the feed rollers of one set into contact with the 5 platen so that the rollers of one set may be independently applied to the platen after the rollers of the other set are applied, and automatically operating means for rendering one set of feed rollers ineffective when 10 the rollers of the other set are withdrawn from the platen.

7. In a typewriting machine, the combination of a platen, a set of margin paper feed rollers, means for applying said feed rollers 15 against the platen with a positive pressure, a second set of margin paper feed rollers spring-pressed against the platen, means for restraining the spring-pressed rollers against the action of their spring means and 20 away from the platen while the feed rollers of the first mentioned set are being positively applied, and means for automatically bringing said second set of feed rollers under control of said restraining means when the 25 feed rollers of the first mentioned set are moved away from the platen.

8. In a typewriting machine, the combination of a platen, a set of paper feed rollers coacting with the platen above the printing 30 line and movable into and out of contact with the platen, a second set of paper feed rollers coacting with the platen above the printing line and connected to move with the first mentioned set of rollers towards 35 and away from the platen and also movable into and out of contact with the platen independently of the first mentioned set of feed rollers, and means for independently and positively locking said second set of feed 40 rollers out of contact with the platen.

9. In a typewriting machine, the combination of a platen, a set of paper feed rollers coacting with the platen above the printing line and movable into and out of contact 45 with the platen, a second set of paper feed rollers coacting with the platen above the printing line and connected to move with the first mentioned set of rollers towards and away from the platen and also movable 50 into and out of contact with the platen independently of the first mentioned set of feed rollers, and automatically operating means for independently locking said second set of feed rollers out of contact with the platen and including manually controlled means 55 for releasing said locking means.

10. In a typewriting machine, the combination of a platen, a set of paper feed rollers coacting with the platen above the printing line and movable into and out of contact with the platen, a second set of paper feed rollers coacting with the platen above the printing line and movable into and out of contact with the platen independently of the first mentioned set of feed 60 rollers.

ers, and means for locking said second set of feed rollers out of contact with the platen, said locking means comprising a spring-pressed pivoted link having a locking notch therein to engage a pin shiftable with 70 said second set of feed rollers and also having a finger piece by which said link may be shifted in opposition to its spring pressure to free the locking notch from said pin.

11. In a typewriting machine, the combination of a platen, a set of primary paper feed rollers cooperative therewith, a second set of secondary paper feed rollers cooperative with the platen, means for operatively connecting the two sets of feed rollers to 80 move together towards and away from the platen, means for applying the set of primary feed rollers to the platen, independently actuated means for controlling the application of the secondary feed rollers to 85 the platen, and automatically operating means controlled by the release of the primary feed rollers for releasing said secondary feed rollers.

12. In a typewriting machine, the combination of a platen, a set of primary paper feed rollers cooperative therewith, a second set of secondary paper feed rollers cooperative with the platen, means for operatively connecting the two sets of feed rollers to 95 move together towards and away from the platen, means for applying the set of primary feed rollers to the platen, independently actuated means for controlling the application of the secondary feed rollers to 100 the platen, and automatically operating means controlled by the release of the primary feed rollers for releasing said secondary feed rollers and for thereafter maintaining them ineffective of application to 105 the platen except by an operation of the independently actuated controlling means therefor.

13. In a typewriting machine and billing mechanism therefor, the combination of a platen, two sets of paper feed rollers cooperative therewith, the rollers of one set being margin feed rollers and the rollers of the other set being restricted to a field of operation intermediate the margin feed rollers, independently actuated means for controlling the application of the feed rollers of the two sets to the platen, and automatically operating means for releasing one set of feed rollers from the platen when the feed rollers of the other set are released.

14. In a typewriting machine and billing mechanism therefor, the combination of a platen, a set of primary margin paper feed rollers cooperative therewith, means including a finger piece for controlling the application of said feed rollers to the platen, a second set of secondary paper feed rollers cooperative with the platen and restricted to a field of operation intermediate said 120

margin feed rollers, means including an independently actuated finger piece for controlling the application of said secondary feed rollers to the platen, and automatically 5 operating means for releasing said secondary feed rollers from the platen when said primary feed rollers are released.

15. In a typewriting machine, the combination of a platen, a set of primary feed 10 rollers cooperative therewith, a shiftable spindle on which said feed rollers are carried and by a bodily movement of which said feed rollers are applied to the platen, means for shifting said spindle bodily, a 15 set of secondary paper feed rollers carried by said spindle out of axial alignment with said primary feed rollers, and independently actuated means cooperative with said secondary feed rollers to control the shifting thereof on said spindle and thus control the application of the secondary feed rollers to the platen.

16. In a typewriting machine, the combination of a platen, a set of primary feed 25 rollers cooperative therewith, a shiftable spindle on which said feed rollers are carried and by a bodily movement of which said feed rollers are applied to the platen, means for shifting said spindle bodily, a set of 30 secondary paper feed rollers carried by said spindle out of axial alignment with said primary feed rollers, independently actuated means cooperative with said secondary feed rollers to control the shifting thereof on said 35 spindle and thus control the application of the secondary feed rollers to the platen, and automatically operating means by which the release of the primary feed rollers is effective to release the secondary feed rollers but 40 the application of the primary feed rollers to the platen is ineffective to apply the secondary feed rollers to the platen.

17. In a typewriting machine, the combination of a platen, a set of primary feed 45 rollers cooperative therewith, a shiftable spindle on which said feed rollers are carried and by a bodily movement of which said feed rollers are applied to the platen, means for shifting said spindle bodily, a 50 carrier pivoted on said spindle, a set of secondary paper feed rollers carried by said carrier out of axial alignment with the primary feed rollers, and independent means for controlling the pivotal movement of said 55 carrier on the spindle to control the application of the secondary feed rollers to the platen.

18. In a typewriting machine, the combination of a platen, a set of primary feed 60 rollers cooperative therewith, a shiftable spindle on which said feed rollers are carried and by a bodily movement of which said feed rollers are applied to the platen, means for shifting said spindle bodily, a carrier pivoted on said spindle, a set of sec-

ondary paper feed rollers carried by said carrier out of axial alignment with the primary feed rollers, a finger piece for controlling the pivotal movement of said carrier to control the application of the secondary feed rollers to the platen, and means automatically controlled by a shifting of the primary feed rollers away from the platen for controlling said pivoted carrier to prevent an application of the secondary feed 75 rollers to the platen by subsequent applications of the primary feed rollers to the platen.

19. In a typewriting machine, the combination of a platen, a set of primary feed 80 rollers cooperative therewith, a shiftable spindle on which said feed rollers are carried and by a bodily movement of which said feed rollers are applied to the platen, means for shifting said spindle bodily, a 85 carrier pivoted on said spindle, a set of secondary paper feed rollers carried by said carrier out of axial alignment with the primary feed rollers, a link connected to said carrier, automatically operating latching means cooperative with said link when the primary feed rollers are released, and a finger piece on said link for releasing it from its latching means and controlling the application of the secondary feed rollers to the 90 platen.

20. In a typewriting machine and billing mechanism therefor, the combination of a platen, a spindle shiftable towards and away from the platen, a set of paper feed 100 rollers carried thereby and shiftable into and out of contact with the platen by said shifting movement of the spindle, a second set of paper feed rollers carried by said spindle, and means operable independently of the operation of said spindle for rendering said second set of feed rollers effective to coat with the platen to feed a work sheet or 105 sheets.

21. In a typewriting machine, the combination of a platen, a spindle shiftable towards and away from the platen, a set of paper feed rollers carried thereby and shiftable into and out of contact with the platen by said shifting movement of the spindle, a second set of paper feed rollers carried by said spindle, means operable independently of said spindle for rendering said second set of feed rollers effective to coat with the platen and for locking them in ineffective relation, 115 and automatically operating means for rendering said locking means effective when the spindle is moved away from the platen.

22. In a typewriting machine, the combination of a platen, two sets of paper feed 125 rollers, a finger piece, means controlled thereby for moving both sets of feed rollers towards and away from the platen and for bringing one of said sets in contact with the platen, and independently operated means 130

for moving the other set of feed rollers in contact with the platen after the first set has been brought into contact therewith by an actuation of said finger piece.

- 5 23. In a typewriting machine and billing mechanism therefor, the combination of a platen, a main feed roller carrier movable towards and away from the platen, a set of paper feed rollers carried by said carrier and moved thereby into contact with the platen, a supplemental feed roller carrier carried by said main carrier and capable of movement thereon, and a second set of paper feed rollers carried by the supplemental carrier and which are brought into contactive feeding engagement with the platen by an independently controlled movement of the supplemental carrier on the main carrier.
- 10 24. In a typewriting machine and billing mechanism therefor, the combination of a platen, a main feed roller carrier movable towards and away from the platen, a set of paper feed rollers carried by said carrier and moved thereby into contact with the platen, a supplemental feed roller carrier carried by said main carrier and capable of movement thereon, a second set of paper feed rollers carried by the supplemental carrier and which are brought into contactive feeding engagement with the platen by an independently controlled movement of the supplemental carrier on the main carrier, and means operable at will for locking said supplemental carrier in fixed relation to said main carrier and with the second set of feed rollers released from the platen.

25. In a typewriting machine, the combination of a platen, a main feed roller carrier movable towards and away from the platen, a set of paper feed rollers carried by said carrier and moved thereby into contact with the platen, a supplemental feed roller carrier carried by said main carrier and capable of movement thereon, a second set of paper feed rollers carried by the supplemental carrier and which are brought into contact with the platen by an independently controlled movement of the supplemental carrier on the main carrier, means operable at will for locking said supplemental carrier in fixed relation to said main carrier and with the second set of feed rollers released from the platen, and automatically operating means for engaging said locking means when the main carrier is shifted away from the platen.

26. In a typewriting machine, the combination of a platen, a spindle movable towards and away from the platen, a set of paper feed rollers carried by said spindle and moved thereby into contact with the platen, a second spindle carried by said first mentioned spindle and movable there-
65 with and having an independent movement

thereon, a second set of paper feed rollers carried by said second spindle and arranged to turn bodily around the axis of said first mentioned spindle and thus be brought into contact with the platen, manually controlled means independently actuated to control such bodily movement of said second set of feed rollers into contact with the platen, and automatically operating means for preventing a bodily movement of the second set 75 of feed rollers into contact with the platen.

27. In a typewriting machine, the combination of a platen, paper feed rollers coacting therewith, hand controlled means operable at will for simultaneously moving 80 said feed rollers to or from the platen and exerting a positively applied pressure of said feed rollers against the platen, and adjustable means by which the positively applied pressure of the feed rollers may be 85 varied.

28. In a typewriting machine, the combination of a platen, paper feed rollers coacting therewith, spring means which tend to move the feed rollers away from the 90 platen, manually controlled means operable at will for overcoming said spring means and applying the feed rollers to the platen with a positive pressure, means for maintaining indefinitely the positively applied 95 pressure of the feed rollers against the platen, and adjustable means by which the positively applied force of the feed rollers may be varied without varying the operation of 100 said manually controlled means.

29. In a typewriting machine, the combination of a platen, a set of paper feed rollers, means for guiding said feed rollers for substantially rectilinear shifting movement towards and from the platen, means for forcing said feed rollers in contact with the platen with a positively applied pressure, and means for adjusting said guiding 105 means transversely of the substantially rectilinear shifting movement of said feed rollers and thereby vary the amount of pressure exerted against the platen by said positively applied feed rollers.

30. In a typewriting or like machine, the combination of a cylindrical platen, a set of paper feed rollers that coact with the platen to one side of the printing line, means for effecting substantially a rectilinear movement of said feed rollers into and out of contact with the platen and causing said feed rollers to be positively pressed against the platen, and adjustable means for varying the path of rectilinear movement of said feed rollers and thereby cause the feed rollers to be applied with an increased or 115 decreased pressure.

31. In a typewriting or like machine, the combination of a carriage, a cylindrical platen carried thereby, paper feed rollers which coact with the platen to one side of 120 125 130

the printing line, guiding means maintained in any one of a number of fixed positions on the carriage for guiding said feed rollers in their movement towards and from the 5 platen, means for thus moving said feed rollers and causing them to be applied with a positive pressure against the platen, and means for adjusting said guiding means to different set positions on the carriage and 10 thereby vary the pressure exerted by the feed rollers against the platen when they are moved to effective position.

32. In a typewriting machine, the combination of a carriage, a platen carried thereby, paper feed rollers, a spindle on which 15 said feed rollers are mounted, guides on the carriage by which said spindle is mounted for bodily rectilinear movement towards and away from the platen, means including a 20 toggle for shifting said spindle and applying the feed rollers with a positive pressure when the toggle is straightened, and means for adjusting said guides and thereby determining the amount of force exerted by 25 the feed rollers against the platen when the toggle is straightened.

33. In a typewriting machine, the combination of a platen; paper feed rollers mounted for movement towards and away 30 from the platen; and means for thus moving said feed rollers, said means including toggle members which in moving to the straight line position force the feed rollers towards the platen and which when substantially in 35 the straight line position press the feed rollers to effective position against the platen with a positive pressure, and adjustable means that enable the straightening of the toggle to apply the feed rollers against the 40 platen with more or less force depending on the adjustment of said adjustable means.

34. In a typewriting machine, the combination of a platen; paper feed rollers; a spindle on which said feed rollers are 45 mounted; means for guiding said spindle to receive a shifting movement towards and from the platen for shifting the feed rollers into and out of contact therewith; manually controlled means for shifting said spindle, said manually controlled means comprising a toggle coating with each end of the spindle, a finger piece, and connections therefrom for simultaneously straightening both toggles to apply the feed rollers; and 55 adjustable means that enable the straightening of said toggles to apply the feed rollers against the platen with more or less force depending on the adjustment of said adjustable means.

35. In a typewriting machine, the combination of a platen; paper feed rollers mounted for movement towards and away 60 from the platen; means for thus moving said feed rollers, said means including toggle members which in moving to the straight

line position force the feed rollers towards the platen and which when substantially in the straight line position press the feed rollers to effective position against the platen with a positive pressure and spring 70 returning means which tend to move the feed rollers away from the platen; and spring detaining means which limit the motion of the feed rollers away from the platen under the action of said spring returning means. 75

36. In a typewriting machine, the combination of a carriage, a platen carried thereby, paper feed rollers, a spindle on which 80 said feed rollers are mounted, guides on the carriage by which said spindle is mounted for bodily rectilinear movement towards and from the platen, a toggle at each end of said spindle controlling its movement, a rock shaft on which one member of each toggle is fixed to control the action of the toggles, and a spring detent with which said spindle coacts to limit the extent of return movement of the toggle members when the toggle is broken from its 85 substantially straight-line position.

37. In a typewriting machine, the combination of a platen, feed rollers movable into and out of contact with the platen, means for thus moving said feed rollers including 90 a toggle the members of which are substantially in the straight-line position when the feed rollers are pressed against the platen, a spring which exerts its force to draw said toggle members towards each other when the toggle is broken from substantially its 95 straight-line position, and a spring detent which limits the motion of said toggle members under the action of said spring. 100

38. In a typewriting machine, the combination of a platen, paper feed rollers cooperative therewith, means for exerting a positively applied pressure of said feed rollers against the platen, means for releasing said feed rollers from the platen, and means for holding said rollers in a given intermediate position between the applied and fully released positions. 105

39. In a typewriting machine, the combination of a platen, paper feed rollers cooperative therewith, means for exerting a positively applied pressure of said feed rollers against the platen, means for releasing the positively applied pressure of the feed rollers against the platen, spring means which then tend to move said feed rollers away from the platen, and detent means which tend to limit the extent of movement of said feed rollers away from the platen 110 under the action of said spring means. 120

40. In a typewriting machine, the combination of a platen, paper feed rollers cooperative therewith, means for exerting a positively applied pressure of said feed rollers against the platen, means for releasing 125 130

the positively applied pressure of the feed rollers against the platen, spring means which then tend to move said feed rollers away from the platen, and detent means which prevent an accidental displacement of said feed rollers from their fully released position.

41. In a typewriting machine, the combination of a platen, paper feed rollers cooperative therewith, means for exerting a positively applied pressure of said feed rollers against the platen, means for releasing the positively applied pressure of the feed rollers against the platen, spring means which then tend to move said feed rollers away from the platen, detent means which tend to limit the extent of movement of said feed rollers away from the platen under the action of said spring means, and detent means which prevent an accidental displacement of said feed rollers from their fully released position.

42. In a typewriting machine, the combination of a platen, paper feed rollers cooperative therewith, means for exerting a positively applied pressure of said feed rollers against the platen, means for releasing said feed rollers from the platen, a line indicator shiftable into and out of effective position, means for automatically shifting said line indicator from the normally effective position to an ineffective position when said feed rollers are moved to the fullest extent of their releasing movement away from the platen but which enable said feed rollers to be moved away from the platen to a lesser extent without actuating said indicator, and a detent for holding said feed rollers in the released position they attain just before the line indicator is actuated.

43. In a typewriting machine, the combination of a platen, paper feed rollers cooperative therewith, means for exerting a positively applied pressure of said feed rollers against the platen, means for releasing said feed rollers from the platen, a line indicator shiftable into and out of effective position, means for automatically shifting said line indicator from the normally effective position to an ineffective position when said feed rollers are moved to the fullest extent of their releasing movement away from the platen but which enable said feed rollers to be moved away from the platen to a lesser extent without actuating said indicator, a detent for holding said feed rollers in the released position they attain just before the line indicator is actuated, and a detent for holding said feed rollers against accidental displacement from their fully released position.

44. In a typewriting machine, the combination of a platen, paper feed rollers cooperative therewith, means for exerting a positively applied pressure of said feed rollers

against the platen, means for releasing said feed rollers from the platen, a paper deflector shiftable into and out of effective position, means for automatically shifting said deflector from the normally ineffective position to an effective position when said feed rollers are moved to the fullest extent of their releasing movement away from the platen but which enable said feed rollers to be moved away from the platen to a lesser extent without actuating said deflector, and a detent for holding said feed rollers against accidental displacement from their fully released position.

45. In a typewriting machine and billing mechanism therefor, the combination of a platen, two sets of feed rollers, the feed rollers of one set being restricted to a field of operation intermediate the rollers of the other set, a finger piece, and means by which a complete movement of said finger piece in one direction is effective to move both sets of feed rollers away from the platen and a complete movement of the finger piece in the opposite direction is effective to apply one set only of said feed rollers to the platen.

46. In a typewriting machine and billing mechanism therefor, the combination of a platen, two sets of feed rollers mounted for movement into and out of contact with the platen, and controlling means for simultaneously moving and maintaining both sets of feed rollers out of contact with the platen and for independently applying the feed rollers of the two sets, said controlling means including a finger piece on the actuation of which in one direction both sets of feed rollers will be withdrawn from the platen and on the actuation of which in the opposite direction one set only of feed rollers will be applied to the platen.

47. In a typewriting machine and billing mechanism therefor, the combination of a platen, two sets of feed rollers mounted for movement into and out of contact with the platen, and controlling means for simultaneously moving and maintaining both sets of feed rollers out of contact with the platen and for independently applying the feed rollers of the two sets, said controlling means including a finger piece on the actuation of which in one direction both sets of feed rollers will be withdrawn from the platen and on the actuation of which in the opposite direction one set only of feed rollers will be applied to the platen, and a second finger piece by a subsequent actuation of which the other set of feed rollers will be applied to the platen.

48. In a typewriting machine and billing mechanism therefor, the combination of a platen, two sets of margin feed rollers arranged above the printing line and mounted for movement into and out of contact with the platen, and controlling means for simul-

aneously moving and maintaining both sets of margin feed rollers out of contact with the platen and for independently applying the margin feed rollers of the two sets, said 5 controlling means including a finger piece on the actuation of which in one direction both sets of feed rollers will be withdrawn from the platen and on the actuation of which in the opposite direction one set only 10 of feed rollers will be applied to the platen.

49. In a typewriting machine and billing mechanism therefor, the combination of a platen, two sets of margin feed rollers arranged above the printing line and mounted 15 for movement into and out of contact with the platen, and controlling means for simultaneously moving and maintaining both sets of margin feed rollers out of contact with the platen and for independently applying 20 the margin feed rollers of the two sets, said controlling means including a finger piece on the actuation of which in one direction both sets of feed rollers will be withdrawn from the platen and on the actuation of 25 which in the opposite direction one set only of feed rollers will be applied to the platen, and a second finger piece by a subsequent actuation of which the other set of margin feed rollers will be applied to the platen.

30 Signed at the borough of Manhattan, city of New York, in the county of New York, and State of New York this 21st day of October, A. D. 1926.

FREDERICK A. HART.
